UNITED STATES PATENT OFFICE.

EDWARD G. BUDD, OF PHILADELPHIA, PENNSYLVANIA, ASSIGNOR TO HALE-KILBURN METAL COMPANY, OF PHILADELPHIA, PENNSYLVANIA, A CORPORATION OF PENNSYLVANIA.

CUSHION.

No. 884,706.

Specification of Letters Patent. Patented April 14, 1908.

Application filed April 7, 1906. Serial No. 310,459.

To all whom it may concern:

Be it known that I, EDWARD G. BUDD, a citizen of the United States, residing at Philadelphia, in the county of Philadelphia and State of Pennsylvania, have invented 5 certain new and useful Improvements in Cushions, (Case A,) of which the following is a specification.

This invention relates to cushions and 10 while not limited to those for any particular use, the invention will find its greatest utility in seat and back-cushions for seats of the type commonly employed in cars.

In the construction of a car seat in accordance with my invention, metallic parts are 15 preferably employed to a large extent, these being formed of sheet metal which may be readily pressed to the desired form at relatively small expense. The frame work of the 20 cushion is preferably constructed in this manner and may be of rectangular shape with one or more cross braces extending between opposite sides or across the corners thereof, the shape of the frame-sections and 25 cross braces and the manner in which they are combined being such that a rigid structure is obtained which will not be distorted from its proper shape under the ordinary conditions of use. In the manufacture of 30 cushions of this type, some difficulty has been experienced heretofore in securing the edges of the covering material which extends over the springs or upholstery.

My invention aims to overcome this difficulty and this is accomplished in a simple, reliable and effective manner, by providing a groove in each of the frame sections such that when they are assembled a continuous groove is formed extending around the entire periphery of the cushion and in this groove I place 40 a strip of wood or similar material to which the covering may be secured in any suitable manner as by tacking it thereto, the edge of the material being concealed by the usual beading. The strip may be held in its seat within the groove by wedging it therein or by 45 nails or screws extending through openings in the frame. In the case of a seat-back which is held by back-supporting arms, 50 short lengths of the strip may be omitted at the bottom of the sides of the back thus providing grooves in which such arms may fit and coact directly with the frame of the seat back; this construction is of particular utility

when it is desired to have the seat-back detachable. Suitable springs are provided for yieldingly supporting the surface material of the cushion and these may be the usual spiral springs or, if desired, I may use one or more broad flat springs extending across the 55 entire frame, these being self-sustaining or sustained by some additional means, this latter construction enabling me to make the cushion thinner without sacrificing strength and resiliency.

I have illustrated the features of my invention as embodied in a back cushion for a car seat in the accompanying drawings in which

Figure 1 is an elevation of the cushion 70 broken away and sectioned in part, Fig. 2 is an end view, Fig. 3 is a section on line 3—3 of Fig. 1, Fig. 4 is a section through the lower part of one of the end sections of the frame showing the manner of supporting the seat- 75 back, Fig. 5 is a section on line 5—5 of Fig. 1, Fig. 6 is a section on line 6—6 of Fig. 1, Fig. 7 is a section on line 7—7 of Fig. 1, Fig. 8 is a section on line 8—8 of Fig. 7, and Figs. 9 and 10 are an elevation and a section on line 9—9 80 of Fig. 9, respectively, of a modification.

Referring to these drawings, the frame of the cushion is formed of pressed sheet metal frame-sections secured together in rectangular form; four frame-sections may be employed or if desired only two sections may be used, one indicated by the numeral 1 bent to form the sides and top of the frame to provide rounded corners at the top and secured at its ends to a straight bottom section 2, 85 90 Each of the frame-sections is formed to provide a lengthwise groove at the center thereof and inwardly turned flanges at the sides.

Figs. 5 and 7 best illustrate the construction of the frame-section 1, the groove being 95 indicated at 3 and the flanges at 4 and 5. The bottom member 2 is of similar construction except that it is of less width as illustrated in Fig. 8, the flanges being indicated by the numerals 6 and 7. The flanges 4 and 100 5 on the frame-section 1 are curved in the direction of their length, as best shown in Fig. 2, and when the covering material of the cushion is applied to the frame, it overlies these flanges and is shaped thereby to the 105 curvature desired for the surface material of the cushion. The bottom member 2 is enlarged at the ends as shown in Figs. 7 and

8 so that the flanges 6 and 7 thereof fit snugly within the flanges 4 and 5 of the section 1. The two frame-sections may be united by rivets extending through the flanges, but in order to obtain greater strength I prefer to provide an additional strengthening member or brace 8 as shown in Figs. 1 and 7; this member has two end portions 9 which abut against the flanges of the end frame-section 10 and a web 10 connecting these end portions and to afford greater strength a second web 10' may be provided at right angles to the web 10, the whole being formed integral of pressed sheet metal.

15 The parts are assembled with the strengthening members lying between the flanges 6 and 7 of the bottom section 2 and the flanges 4 and 5 of the section 1 overlying the flanges 6 and 7, as shown in Fig. 7; rivets 11 are then inserted through each of the pairs of flanges and one of the end portions 9 to hold the parts firmly together. It will be seen that the frame thus assembled has a groove 3 running around the entire periphery, the purpose whereof will be fully explained hereinafter. In order to stiffen the frame, I employ a cross-brace 12 extending between the side members of the frame and secured at its ends thereto. This cross-brace is formed of two interlocking sheet metal parts 13 and 14 each having a flange 15 at one edge and a fold 16 at the other and the flange of each part lying within the fold of the other as shown in Fig. 6. At the ends of the cross-brace the two parts thereof are separated (Fig. 5) and bent to fit directly under the flanges 4 and 5 of the sides of the frame to which they are secured by rivets 17. In order to further stiffen the frame, I preclude movement of one of the parts of the cross-brace 12 upon the other by indenting the overlapping flanges of the two parts at intervals throughout their length as indicated at 17'. It will be seen that a frame constructed in this manner is of great strength and will not become twisted or distorted throughout a long period of use.

The cushion illustrated in the drawings is adapted for use as a back for a seat of the 50 "walkover" type in which both sides of the cushion are used and I therefore provide, for supporting the surface material of the cushion, flat springs 18 extending across the cushion on either side thereof and spiral 55 springs 19 supporting these flat springs. The flat springs 18 are secured at their ends by rivets 20 to the flanges of the frame-sections and each of the spirals 19 lies between and is secured at its ends to two of the flat springs 18 on opposite sides of the cushion. The covering material, as for instance a first canvas and an outer covering, overlies the flat springs 18 and is secured at its edges in the following manner. In the grooves 3 extending 60 around the frame, I insert a strip of wood

21 which may be secured in position by wedging it in the groove or by screws or nails extending through openings provided in the frame. When this strip is firmly seated in the groove the covering material 22 may be drawn tightly over the flat springs and tacked thereto and the edges of the material may be covered by a beading 23. This provision of a tacking strip running around the entire frame on the outer side thereof forms 75 a very convenient means for securing the covering material upon a metallic frame and one which permits of manufacturing the cushions at relatively small expense of time and labor.

80 For supporting a seat back it is usual to provide two back-supporting arms or levers which are pivoted at their lower ends and at their upper ends carry the back cushion. The construction of cushion illustrated and 85 described herein can be readily and securely mounted upon such arms or levers in a manner permitting the latter to coact directly with the metallic frame by omitting the tacking strips 21 at certain points on the 90 frame and forming the back supporting levers to enter the groove 3 at the points where the tacking strip has been omitted. If the back cushion is to be detachable, the tacking strip 21 extends down at the sides 95 of the frame preferably to a point somewhat below the middle and from this point down, the covering material, instead of overlapping the groove 3 is tacked or sewed to the frame adjacent to the edge of the groove, holes 100 being provided in the metal for this purpose. When the covering has been secured in this manner, a cover plate 24 is secured to frame-member 2 at the sides of the groove 3. There are thus provided two openings extending up into the sides of the frame each formed by the groove 3 and the cover plate 24, for the reception of the back-supporting levers 25 and permitting the back to be quickly detached therefrom. When the 110 back is in position the levers 25 bear against the sides of the groove 3, that is directly against the metal of the frame so that the back is firmly supported in position.

In Figs. 9 and 10 I have illustrated a modification of the cushion shown in the other figures, the difference between the two types being in the manner of yieldingly supporting the surface material of the cushion. In these figures two broad flat springs 26 are 115 provided extending across the frame from side to side at about the middle of the cushion. These springs are flanged inwardly at the sides to stiffen them. It will be understood that with this form of spring support 120 for the cushion covering, the features of my invention relating to the frame construction and the means for securing the edges of the covering may be employed as in the form 125 illustrated in the other figures.

Having described my invention, what I claim as new and desire to secure by Letters Patent, is:

1. In a cushion, the combination of a frame formed of sheet metal frame sections secured together, said sections having inwardly extending flanges at the sides thereof, flat springs at both sides of said cushion secured at their ends to said flanges, covering material overlying said springs and yieldingly positioned thereby, and means for securing the edges of said material to said metallic frame, substantially as described.

2. In a cushion, the combination of a frame formed of sheet metal frame sections secured together, said sections having inwardly extending flanges at the sides thereof, a brace extending across said frame and secured at its ends to said flanges, flat springs at both sides of said cushion secured at their ends to said flanges, covering material overlying said springs and yieldingly positioned thereby, and means for securing the edges of said material to said metallic frame, substantially as described.

3. In a cushion, the combination of a frame formed of sheet metal frame sections secured together; each of said sections having inwardly turned flanges at the sides thereof and a groove intermediate said flanges, springs supported on said frame, covering material extending over both sides of said frame and yieldingly positioned on both sides of the frame by said springs, and means coacting with said groove for securing the edges of said covering material to said metallic frame, substantially as described.

4. In a cushion, the combination of a frame formed of pressed sheet metal frame sections secured together, each of said sections having inwardly turned flanges at the sides thereof and a groove intermediate said flanges, a metallic brace extending across said frame and secured at its ends to said flanges, springs supported on said frame, covering material extending over both sides of said frame and yieldingly positioned by said springs, and means coacting with said grooves for securing the edges of said covering material to said metallic frame, substantially as described.

5. In a cushion, the combination of a metallic frame formed of frame sections secured together at their ends, each of said sections consisting of a single piece of sheet-metal pressed to provide flanges at the lateral edges extending inwardly of the frame and a groove on the outer side of the section intermediate and parallel to the lateral edges, and certain of said flanges being curved lengthwise thereof strips located in the grooves in said sections, springs supported on the frame, and a covering extending over both sides of said frame and yieldingly sustained on both sides by said springs, said covering overlying

and being shaped by said flanges and being secured at its edges to said strips, substantially as described.

6. In a cushion, the combination of a metallic frame formed of frame sections secured together at their ends, each of said sections consisting of sheet metal pressed to provide flanges at the lateral edges extending inwardly of the frame and a groove on the outer side of the section intermediate the lateral edges, and certain of said flanges being curved lengthwise thereof strips located in the grooves in said sections, springs supported on the frame, and secured at their ends to said flanges, and a covering extending over both sides of said frame and yieldingly sustained on both sides by said springs, said covering overlying and being shaped by said flanges and being secured at its edges to said strips, substantially as described.

7. In a cushion, the combination of a metallic frame formed of frame sections secured together at their ends, each of said sections consisting of a sheet-metal strip pressed to provide a flange along one edge extending inwardly of the frame and a groove on the outer side of the section spaced apart from said flange, certain of said flanges being curved lengthwise thereof, strips located in the grooves in said sections, springs supported on the frame, and a covering extending over said springs and frame sections and being yieldingly sustained by said springs and shaped by said flanges, the edges of said covering being secured to said strips, substantially as described.

8. In a cushion, the combination of a rectangular metallic frame formed of two frame sections secured together at their ends, each of said sections consisting of a sheet-metal strip pressed to provide a flange along one edge extending inwardly of the frame and a groove on the outer side of the section spaced apart from said flange, certain of said flanges on the frame sections being curved in the direction of their length, and one of said sections being bent to form a plurality of the sides of the frame and to form rounded corners, strips located in the grooves in said sections, springs supported on the frame, and a covering extending over said springs and frame sections and yieldingly sustained by the springs and shaped by said flanges, said covering being secured at its edges to said strips, substantially as described.

9. In a cushion, the combination of a sheet metal frame each of the members whereof has flanges at the lateral edges thereof and a groove intermediate the edges, flat springs secured at their ends to said flanges, a strip located in the grooves in the members of the frame and a covering overlying said springs and secured at the edges to said strip, substantially as described.

10. In a cushion, the combination of a

- sheet metal frame each of the members whereof has flanges at the edges thereof and a groove intermediate the edges, a brace extending across the frame and secured at its ends to said flanges, springs supported on said frame, a strip located in said groove, and a covering extending over said springs and secured at its edges to said strip, substantially as described.
- 10 11. In a cushion, a frame formed of sheet metal frame sections secured together, and a brace extending across and secured at its ends to said frame, said brace being formed in two parts lying parallel one to the other and interlocked to prevent movement of one part relatively to the other lengthwise of the brace, substantially as described.
- 15 12. In a cushion, a frame formed of sheet metal frame sections secured together, said sections having flanges at the sides thereof, and a brace extending across said frame, said brace being formed in two parts secured together by flanges and folds inclosing said flanges formed in said parts and said parts 20 being spread at their ends and secured to the flanges of said frame sections, substantially as described.
- 25 13. In a seat-back cushion, the combination of a frame formed of sheet metal frame sections having grooves in the outer faces thereof, strips filling said grooves except for the portions thereof at the lower part of the side edges of the cushion, a covering drawn over said frame and secured to said strips, and back-supporting levers whose ends enter the sockets formed by the portions of said 30 groove at the lower part of the side edges of the cushion, substantially as described.
- 35 14. In a seat back cushion, the combination of a sheet metal frame having a peripheral groove, strips of wood filling said groove except for portions thereof at the lower part of the side edges of the cushion, a covering extending over said frame and secured at its edges to said strip, cover plates secured to the frame over the portions of the groove not occupied by said strip, and back-supporting levers whose ends enter the sockets formed by said grooves and plates, substantially as 40 described.
- 45 15. In a cushion, a frame formed of sheet metal frame sections secured together, each of said sections having inwardly extending flanges at the lateral edges thereof and a brace extending between the flanges of a frame section having a body portion and integral end portions bent at an angle to the body portion and means securing said end portions to said flanges, substantially as described.
- 50 16. In a cushion, the combination of a frame formed of sheet-metal frame sections secured together, each of said sections having inwardly turned flanges at the sides thereof and a groove intermediate said flanges, springs supported on said frame, covering material extending over both sides of said frame and the inwardly-turned flanges thereon and being shaped by said flanges and yieldingly positioned by said springs, and means coacting with said groove for securing the edges of said covering to said metallic frame, substantially as described.
- 55 17. In a cushion, the combination of a metallic frame formed of frame sections secured together at their ends, each of said sections consisting of a sheet-metal strip pressed to provide a flange along one edge extending inwardly of the frame and a groove on the outer side of the section intermediate the lateral edges, strips located in the grooves in 60 said sections, springs extending across said frame and secured at their edges to said flanges, and a covering yieldingly positioned by said springs and secured at its edges to said strips, substantially as described.
- 65 18. In a cushion, the combination of a sheet-metal frame, each of the members whereof has an integral flange extending inwardly of the frame at the lateral edges thereof and a groove on the outer side of the member intermediate the lateral edges thereof, a metallic brace extending across the frame and secured at its ends to said flanges, springs supported on the frame, strips located in said grooves, and covering material extending over both sides of the cushion and secured to said strips, said covering being shaped by said flanges and spaced apart on 70 both sides of the cushion from said brace, substantially as described.
- 75 19. In a cushion, a frame formed of sheet-metal frame sections secured together, said sections having flanges at the sides thereof, a brace extending across said frame, said brace being secured at each of its ends to the two flanges on the frame section, springs supported on said frame, and a covering extending over and yieldingly sustained by said springs, its edges being secured to said frame, said brace being unsecured to and spaced apart from said covering, substantially as 80 described.
- 85 1906 This specification signed and witnessed this 31st day of March, 1906.
